INVENTOR
BY Victor J. Evans & Co.

ATTORNEY

UNITED STATES PATENT OFFICE

JOHN J. OLSEN, OF CLEVELAND, OHIO

ROPE HOLDER

Application filed July 29, 1932. Serial No. 626,119.

This invention relates to rope gripping holders and its general object is to provide a holder of that character that is primarily designed for clothes lines, and which is automatic in its action in gripping the line, as well as the fact that it will hold the line taut under all conditions.

A further object of the invention is to provide a clothes line holder that is capable of receiving lines of various thicknesses, and a line can be associated therewith in an easy and expeditious manner without removing the holder in the event the holder has been fastened to a post or the like.

Another object of the invention is to provide a clothes line assembly that includes separable pulleys and a gripping holder constructed in a manner whereby it is not necessary to thread the line therethrough, as is customary in clothes line devices now in general use.

A still further object of the invention is to provide a rope gripping holder of the character set forth, that is simple in construction, inexpensive to manufacture, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:—

Figure 1 is a top plan view illustrating my device in use.

Figure 2 is a side elevation of the holder in gripping position.

Figure 3 is a longitudinal sectional view taken through the holder with the gripping dog arranged out of contact with the line.

Figure 4 is a sectional view taken approximately on line 4—4 of Figure 2, looking in the direction of the arrows.

Figure 5 is a top plan view of the holder.

Figure 6 is a rear end view thereof.

Figure 7 is a side view of a pulley used in the clothes line assembly.

Figure 8 is a top plan view of said pulley.

Referring to the drawing in detail, and especially to Figure 1 which illustrates a clothes line assembly that includes three posts A, B and C respectively and D indicates a clothes line of the usual type.

The line as shown may be permanently fixed to the post A or suitable fastening means and is thence trained about the grooved wheel 1 of a pulley which includes sectional housing members 2 and 3 having secured thereto a pivot pin 4 for receiving the wheel 1, and these housing members terminate in apertured tongues 5 for the purpose of detachably receiving a bolt and nut connection 6 whereby the housing members may be separated as shown in Figure 7 for the passage of the line D between the same as will be apparent, and the bolt and nut connection receives suitable securing means whereby the pulley may be secured to the post B as shown in Figure 1.

The rope gripping holder is suitably fastened to the post C and includes a housing which is made up of a relatively wide side wall 7 and a relatively narrow side wall 8 for a purpose which will be later described and the side walls are connected by a rear wall 9. The side wall 7 has formed with its forward end an extension 10 that terminates into an eye 11 to receive the fastening means that secures the holder to the post C.

Formed with the side wall 7 is a top wall 12 that is provided with a serrated inner surface to receive the line D as clearly shown in Figures 2 and 3 of the drawing. Pivots secured to the rear end of the top wall 12 is a bifurcated line guide member 13, which is adapted to receive the line D between the arms thereof.

Bridging the side walls 7 and 8 is a pivot pin 14 that has journaled thereon a grooved wheel 15 for the line D as shown, and pivotally secured between the side walls 7 and 8 is a dog 16 which is provided with a serrated jaw 17 at its inner end while its outer or opposite end terminates into a handle 18 that is engageable with the rear wall 9 so as to pre-

vent the jaw 17 from coming in contact with the grooved wheel 15 as will be noted upon inspection of Figure 3. The dog is pivoted upon a pin 19 that bridges the side walls.

5 The relatively narrow side wall 8 is provided with a spider member 20 that includes a semi-circular guard that follows the curvature of the grooved wheel 15 and the spider member 20 cooperates with the extension 10 10 in holding the line trained about the grooved wheel 15.

From the above description and disclosure of the drawing, it will be obvious that I have provided a rope gripping holder that 15 is primarily designed for a clothes line, and it is not necessary to thread the line about the wheel 15, because the line can be inserted laterally through the space provided between the narrow side wall 8 and the top wall 20 12, as best shown in Figure 2. Of course, the bifurcated line guide member is moved upwardly on its pivot when the line is inserted within the holder, and thence the guide member is returned to its normal position as 25 best shown in Figures 2 and 3. When the line is arranged in the holder, the jaw 17 will be disposed in gripping engagement therewith, and as the jaw cooperates with the serrated lower surface of the top wall 12, 30 it will be apparent that when the line is pulled in the direction of the holder, the dog will function automatically to grip the line and therefore the line will be held taut under all conditions.

35 While I have illustrated the use of one pulley in Figure 1, it will be apparent that any number of pulleys may be employed, it depending of course upon the number of sections of clothes lines used.

40 It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A holder for a line comprising a housing including a relatively wide side wall and a relatively narrow side wall, a top wall formed with the relatively wide side wall and being provided with a serrated inner surface, a grooved wheel journaled between the side walls, a dog pivotally secured between the side walls, a serrated jaw formed with the inner end of said dog and cooperating with the serrated wall for gripping the line, a handle formed with said dog and extending from the housing, and a guide for said line and being secured to said top wall.

2. A holder for a line comprising a housing including a relatively wide side wall and a relatively narrow side wall, a rear wall connecting the side walls, a top wall having a

serrated inner surface and formed with the relatively wide side wall, said relatively narrow side wall being spaced from the top wall to provide a line receiving space, a pulley journaled between the side walls, a dog pivotally secured between the side walls, a serrated jaw formed with the dog and cooperating with the serrated wall for gripping the line, a bifurcated guide member for said line and being pivotally secured to the top wall, and an eyed extension formed with said housing.

3. A gripping holder for a line, comprising a housing including a relatively wide side wall and a relatively narrow side wall, a top wall formed with the relatively wide side wall and being provided with a serrated inner surface, said relatively narrow side wall being spaced from the top wall to provide a space for the passage of the line, a grooved pulley journaled between the side walls, a line guard formed with the relatively narrow side wall and following the shape of the pulley, a rear wall connecting the side walls, a line guide secured to the top wall, a dog pivotally secured between the side walls, a serrated jaw formed with the dog and cooperating with the serrated wall for gripping the line, a handle formed with the jaw and engageable with the rear wall to limit pivotal movement of the dog, an extension formed with the wide side wall and terminating into an eye to receive means for fastening the holder to a suitable supporting means.

In testimony whereof I affix my signature.
JOHN J. OLSEN.
